CROSS-REFERENCE TO RELATED APPLICATIONS

This application is a continuation-in-part of application Ser. No. 189,732, filed Oct. 15, 1971, now abandoned, which in turn is a continuation-in-part of application Ser. No. 88,212, filed Nov. 9, 1970, now U.S. Pat. No. 3,755,437. This application is also a continuation-in-part of application Ser. No. 250,907, filed May 8, 1972, which is, in turn, a continuation-in-part of application Ser. No. 189,732, filed Oct. 15, 1971 and of application Ser. No. 88,212, filed Nov. 9, 1970, now U.S. Pat. No. 3,755,437. The disclosures of U.S. Pat. No. 3,755,437, Ser. No. 250,907 and Ser. No. 189,732 are incorporated herein by reference.

DESCRIPTION OF RELATED ART

German application No. 2,131,399 of Badische Anilin-and Soda-Fabrik, published Dec. 28, 1972, discloses the preparation of N,N'-disulfides of N-methylcarbamates by reacting an N-methylcarbamate with a disulfur dihalide.

DESCRIPTION OF THE INVENTION

The compounds of the invention are represented by the formula

wherein R¹ is hydrogen or alkyl of 1 to 6 carbon atoms; R² is alkyl of 1 to 6 carbon atoms or phenyl substituted with up to 4 (0 to 4), preferably up to 2 (0 to 2) fluorine, chlorine, bromine, nitro, alkyl of 1 to 5 carbon atoms, alkoxy of 1 to 4 carbon atoms, or up to 1 (0 to 1) trifluoromethyl or trichloromethyl; R³ and R⁴ individually are hydrogen, alkyl of 1 to 6 carbon atoms or phenyl substituted with up to 4, preferably up to 2, fluorine, chlorine, bromine, nitro, alkyl of 1 to 5 carbon atoms, alkoxy of 1 to 4 carbon atoms, or up to 1 trifluoromethyl or trichloromethyl; and R⁵ is (a) —NR⁶R⁷ wherein R⁶ is hydrogen or alkyl of 1 to 6 carbon atoms and R⁷ is alkyl of 1 to 6 carbon atoms or phenyl substituted with up to 4, preferably up to 2, fluorine, chlorine, bromine, nitro, alkyl of 1 to 5 carbon atoms, alkoxy of 1 to 4 carbon atoms, or up to 1 trifluoromethyl or trichloromethyl; or (b) —OR⁸ wherein R⁸ is phenyl substituted with up to 4, preferably up to 2, fluorine, chlorine, bromine, nitro, alkyl of 1 to 5 carbon atoms, alkoxy of 1 to 4 carbon atoms, or up to 1 trifluoromethyl or trichloromethyl.

Representative alkyl groups which R¹, R², R³, R⁴, R⁶ and R⁷ may represent include methyl, ethyl, n-propyl, isopropyl, n-butyl, t-butyl and hexyl.

Representative aryl groups which R², R³, R⁴, R⁷ and R⁸ may represent include phenyl, o-fluorophenyl, p-fluorophenyl, o-chlorophenyl, m-chlorophenyl, 2,4-dichlorophenyl, 3,5-dichlorophenyl, 3,4-dichlorophenyl, m-bromophenyl, o-trifluoromethylphenyl, p-trifluoromethylphenyl, p-tolyl, p-ethylphenyl, 3,5-methylphenyl, p-nitrophenyl, p-methoxyphenyl, m-

butoxyphenyl, 2-fluoro-4-methylphenyl and 2-nitro-4-chlorophenyl. Preferred aryl groups are phenyl substituted with up to 2 fluorine, chlorine, bromine or alkyl of 1 to 5 carbon atoms. The most preferred aryl groups are phenyl substituted with up to 2 fluorine, chlorine or bromine.

One class of preferred bis-urea sulfides of Formula I (R⁵ equal to —NR⁶R⁷) is that wherein R¹ and R⁶ are hydrogen; R² and R⁴ are the same and are phenyl substituted with up to 2 fluorine, chlorine, bromine, nitro, alkyl, alkoxy or up to 1 trifluoromethyl or trichloromethyl, more preferably phenyl substituted with up to 2 fluorine, chlorine or bromine; and R³ and R⁷ are the same and are alkyl.

Another class of preferred bis-urea sulfides are those wherein R¹ is hydrogen or alkyl, more preferably hydrogen; R² and R³ individually are alkyl or phenyl substituted with up to 2 fluorine, chlorine, bromine, nitro, alkyl, alkoxy or up to 1 trifluoromethyl or trichloromethyl, more preferably phenyl substituted with up to 2 fluorine, chlorine or alkyl; R⁴ is phenyl substituted with up to 2 fluorine, chlorine, bromine, nitro, alkyl, alkoxy, or up to 1 trifluoromethyl or trichloromethyl; R⁶ and R⁷ individually are alkyl.

The most preferred class of bis-urea sulfides are those wherein R¹ and R⁶ are the same and are hydrogen or alkyl, most preferably hydrogen; R² and R⁷ are the same and are phenyl substituted with up to 2 fluorine, chlorine, bromine, nitro, alkyl, alkoxy, or up to 1 trifluoromethyl or trichloromethyl, most preferably phenyl substituted with up to 2 fluorine, chlorine or bromine.

A preferred class of urea-carbamoyl sulfides of Formula I (R⁵ equal to —OR⁸) is that wherein R¹ is hydrogen, R² is alkyl or phenyl substituted with up to 2 fluorine, chlorine, bromine, nitro, alkyl, alkoxy, or up to 1 trifluoromethyl or trichloromethyl, more preferably up to 2 fluorine, chlorine, bromine or alkyl; R³ is alkyl; R⁴ is alkyl; and R⁸ is phenyl substituted with up to 2 fluorine, chlorine, bromine or alkyl, more preferably phenyl substituted with up to 2 alkyl.

Representative bis-urea sulfides of Formula I include: bis-(3-phenyl-1-ureido) sulfide, bis-(1-methyl-3-phenyl-1-ureido) sulfide, bis-(1-methyl-3-o-fluorophenyl-1-ureido) sulfide, bis-(1-methyl-3-p-fluorophenyl-1-ureido) sulfide, bis-(1-methyl-3-m-chlorophenyl-1-ureido) sulfide, bis-(1-methyl-3-[3,4-dichlorophenyl]-1-ureido) sulfide, bis-(1-methyl-3-[2,4-dibromophenyl]-1-ureido) sulfide, bis-(1-methyl-3-[2,4-dibromophenyl]-1-ureido) sulfide, bis-(1-methyl-3-o-nitrophenyl-1-ureido) sulfide, bis-(1-methyl-3-p-methoxyphenyl-1-ureido) sulfide, bis-(1-methyl-3-m-methylphenyl-1-ureido) sulfide, bis-(1-methyl-3-[2-nitro-4-methoxyphenyl]-1-ureido) sulfide, bis-(1-ethyl-3-[2,3,4,5-tetrachlorophenyl]-1-ureido) sulfide, bis-(1-propyl-3-[3,5-diethoxyphenyl]-1-ureido) sulfide, bis-(1-methyl-3-methyl-3-o-chlorophenyl-1-ureido) sulfide, 1-methyl-3-p-chlorophenyl-1-ureido-1'-p-chlorophenyl-3'-methyl-1-ureido sulfide, 1-methyl-3-(2,4-difluorophenyl)-1-ureido-1'-(2-nitro-4-methoxyphenyl)-3'-methyl-1-ureido sulfide, and 1-methyl-3-o-chlorophenyl-1-ureido-1'-chloromethyl-3'-ethyl-1-ureido sulfide.

Representative urea-carbamoyl sulfides of Formula (I) include:

- (1-methyl-3-p-chlorophenyl-1-ureido)-(phenylcarbamoyl) sulfide,
- (1-methyl-3-o-fluorophenyl-1-ureido)-(o-fluorophenyl-N-methylcarbamoyl) sulfide,
- (1-methyl-3-o-nitrophenyl-1-ureido)-(3-bromophenyl-N-methylcarbamoyl) sulfide,
- (3-methyl-1-o-tolyl-1-ureido)-(2,3,4,5-tetra-chlorophenyl-N-methylcarbamoyl) sulfide, and
- (1-methyl-3-o-trifluorophenyl-1-ureido)-(3-sec-butylphenyl-N-methylcarbamoyl) sulfide.

The compounds of the invention are prepared by reacting an N-chlorothio urea and a urea (III, $R^5 = -NR^6R^7$) or a carbamate (III, $R^5 = -OR^8$), as depicted in equation (1):

wherein R^1 , R^2 , R^3 , R^4 and R^5 have the same significance as previously defined, and B is an acid acceptor.

The acid acceptor is an inorganic base, e.g., alkali metal hydroxide, bicarbonate or carbonate, or an organic nitrogen base such as a pyridine compound or a

ether; and cycloalkyl ethers, e.g., dioxane, tetrahydrofuran and tetrahydropyran. Other suitable diluents include nitriles such as acetonitrile and propionitrile; dialkylamides such as dimethylformamide and dialkylsulfoxides such as dimethylsulfoxide. Preferred diluents are chlorinated hydrocarbons of 1 to 2 carbon atoms, such as methylene dichloride, chloroform, carbon tetrachloride and ethylene dichloride. Generally, the amount of diluent employed ranges from 1 to 50 mols per mol of N-chlorothio urea reactant.

The reaction is suitably conducted at a temperature between -20°C . and the boiling point of the diluent, although temperatures between 0° and 50°C . are preferred. The reaction is conducted at or above atmospheric pressure.

The bis-urea sulfide or urea-carbamoyl sulfide prod-

uct is recovered and purified by conventional procedures such as extraction, crystallization, chromatography, etc.

The N-chlorothio urea reactant (II) is prepared in accordance with the following reaction (2):

trialkylamine. Suitable pyridine compounds are pyridine and pyridine compounds of 6 to 10 carbon atoms and of 1 to 2 alkyl groups such as 2-methylpyridine, 2-ethylpyridine, 3-methylpyridine, 3,5-dimethylpyridine, and 2-butylpyridine. Suitable trialkylamines are those wherein the alkyl group contains individually 1 to 4 carbon atoms, such as trimethylamine, triethylamine, tripropylamine and tributylamine. The preferred acid acceptors are pyridine compounds, especially pyridine.

The N-chlorothio urea reactant (II) and the urea or carbamate (III) are employed in substantially equimolar amounts, e.g., the molar ratio of the N-chlorothio urea reactant (II) to the urea or carbamate (III) generally varies from about 1.5:1 to 1:1.5, although molar ratios of (II) to (III) of about 1.2:1 to 1:1.2 are preferred. The molar ratios of acid acceptor to the N-chlorothio urea reactant are also substantially equimolar, e.g., the molar ratio of acid acceptor to N-chlorothio urea reactant varies from about 1.5:1 to 1:1.5, although molar ratios of acid acceptor to N-chlorothio urea reactant of about 1.2:1 to 1:1.2 are preferred.

The reaction depicted in equation (1) is generally accomplished by reacting the N-chlorothio urea reactant (II) and the urea or carbamate (III) in the presence of the acid acceptor in the liquid phase in an inert diluent. Suitable inert diluents for the reaction include alkanes of 5 to 10 carbon atoms, such as hexane, isooctane and decane; aromatic compounds such as benzene and chlorobenzene; oxygenated hydrocarbons such as acyclic alkyl ethers, e.g., dimethoxyethane and dibutyl

ether, where R^1 , R^2 and R^3 have the same significance as previously defined and B' is an acid acceptor.

The acid acceptor is an organic base such as a pyridine compound or a trialkylamine compound. The preferred acid acceptor is a pyridine compound, especially pyridine.

Generally, commercially available sulfur dichloride of reasonable purity, e.g., greater than 90-98% purity, is suitably employed. The sulfur dichloride may contain small amounts of an inhibitor such as tributylphosphate or triethylphosphate.

The sulfur dichloride and the urea (V) are employed in substantially equimolar amounts, e.g., the molar ratio of sulfur dichloride to the urea compound generally varies from about 1.5:1 to 1:1.5, although molar ratios of sulfur dichloride to the urea compound of 1.4:1 to 1.1:1 are preferred. The molar ratios of acid acceptor to sulfur dichloride are also substantially equimolar, e.g., the molar ratio of acid acceptor to sulfur dichloride varies from about 1.5:1 to 1:1.5, although molar ratios of acid acceptor to sulfur dichloride of 1:1 to 1:1.2 are preferred.

In general, the reaction depicted in equation (2) is accomplished by reacting the urea and the sulfur dichloride in the presence of the acid acceptor compound in the liquid phase in an inert diluent, e.g., diluents employed for the reaction of the N-chlorothio urea reactant and the urea or carbamate. The reaction is suitably conducted by adding the sulfur dichloride to a mixture of the urea and the acid acceptor in an inert diluent. Alternatively, the reaction is conducted by

adding a mixture of the urea and acid acceptor to a solution of the sulfur dichloride in an inert diluent. However, the preferred method for conducting the reaction comprises reacting the urea and sulfur dichloride in the presence of a limited amount of free, uncomplexed acid acceptor. This is suitably accomplished by the addition of the acid acceptor to a substantially equimolar mixture of the urea and the sulfur dichloride, so that the mols of free acid acceptor to the total mols of urea reactant and N-chlorothio urea product is less than 0.2:1, preferably less than 0.1:1, and more preferably less than 0.05:1. In other words, during the course of the reaction between the sulfur dichloride and the urea reactant, there should be at least 5 mols of the urea reactant and the N-chlorothio urea product per mol of acid acceptor which is not complexed with hydrochloric acid. Provided that the reaction is conducted with the restricted amount of acid acceptor indicated above, the contacting of the acid acceptor with the mixture of the urea and the sulfur dichloride can be conducted by a variety of procedures. In one modification, the acid acceptor is added in increments, e.g., dropwise, in an inert diluent, if desired, to a mixture of the urea and sulfur dichloride in an inert diluent. In another modification, the acid acceptor is added continuously to a mixture of the urea and sulfur dichloride in an inert diluent.

The N-chlorothio urea is suitably isolated from the reaction mixture by conventional procedures such as extraction, distillation, chromatography, etc. Alternatively, a solution of the N-chlorothio urea in the reaction diluent, preferably after removal of the acid acceptor hydrochloride salt produced in the reaction, is reacted with the urea or carbamate (III) according to equation (1) to produce the compounds of the invention.

The symmetrical bis-urea sulfides of formula (I) are also prepared by reacting a urea and sulfur chloride as depicted in equation (3):

wherein R¹, R², R³ and B' have the same significance as previously defined.

In general, the reaction depicted by equation (3) is accomplished by adding freshly distilled sulfur dichloride to the urea and the acid acceptor. The reaction is preferably accomplished in a suitable inert solvent such as those employed for the reactions depicted in equations (1) and (2).

The reaction temperature is usually between -20°C and the boiling point of the solvent, preferably 0° to 35°C. The reaction time is from 15 minutes to 12 hours. Stoichiometric amounts of the reactants are generally employed, i.e., the molar ratio of urea to sulfur dichloride is about 2:1 and the molar ratio of urea to acid acceptor is about 1:2.

Asymmetrical bis-urea sulfides may also be prepared by the reaction depicted by equation (3) by using two different urea reactants.

EXAMPLES

EXAMPLE 1

Preparation of N-chlorothio-N-methyl-N'-2-fluorophenyl urea

A 5.7 g (0.055 mol) sample of sulfur dichloride was added dropwise to a mixture of 8.4 g (0.05 mol) N-methyl-N'-2-fluorophenyl urea and 4.7 g (0.06 mol) pyridine in 50 ml methylene chloride cooled in an ice bath. After the completion of the addition, the pyridine hydrochloride formed during the reaction was filtered. Hexane was added to the filtrate to precipitate some additional pyridine hydrochloride, which was removed by filtration. Evaporation of the resulting filtrate gave a clear red oil. The nuclear magnetic resonance spectrum of the oil shows an N-methyl singlet at 3.5 ppm (relative to tetramethylsilane). Elemental analysis showed: %S, calc. 13.6, found 13.6; %Cl, calc. 15.1, found 15.4.

EXAMPLE 2

Preparation of N-chlorothio-N-(3,4-dichlorophenyl)-N',N'-dimethyl urea

A 5.7 g (0.055 mol) sample of sulfur dichloride was added dropwise to a mixture of 11.7 g (0.05 mol) of N-(3,4-dichlorophenyl)-N',N'-dimethyl urea and 4.7 g (0.06 mol) pyridine in 50 ml methylene chloride cooled in an ice bath. After the completion of the addition, the pyridine hydrochloride was filtered. Hexane was added to precipitate some additional pyridine hydrochloride, which was removed by filtration. Evaporation of the resulting filtrate gave the product as a clear yellow oil. The NMR showed an N',N'-dimethyl singlet at 3.0 ppm (relative to tetramethylsilane). Elemental analysis showed:

	Calc.	Found
%S	10.7	10.7
%Cl	35.6	35.4
%C	36.1	36.4
%H	3.0	3.2
%N	9.3	8.7

EXAMPLE 3

Preparation of N-chlorothio-N-methyl-N'-3,4-dichlorophenyl urea

A 9.48 g (0.12 mol) sample of pyridine was added dropwise to a slurry of 21.9 g (0.1 mol) N-methyl-N-(3,4-dichlorophenyl) urea and 11.3 g (0.11 mol) sulfur dichloride in 100 ml methylene dichloride at 25°-30°C. After the completion of the addition, pyridine hydrochloride was filtered from the reaction mixture. The NMR spectrum of the reaction mixture showed a singlet at 3.5 ppm (relative to tetramethylsilane) for the N-methyl group of the N-chlorothio-N-methyl-N'-3,4-dichlorophenyl urea product.

EXAMPLE 4

Preparation of N-chlorothio-N,N'-dimethyl urea

Pyridine (9.48 g — 0.12 mol) was added dropwise to a solution of 8.8 g (0.1 mol) N,N'-dimethyl urea and 11.3 g (0.11 mol) sulfur dichloride at 25°–30°C. Pyridine hydrochloride was then filtered from the reaction mixture to give a solution of the N-chlorothio urea product in methylene chloride. The NMR spectrum of the product showed a singlet at 3.5 ppm for the N-methyl group and a doublet at 2.95 ppm for the N'-methyl group.

EXAMPLE 5

1-methyl-3-(3,4-dichlorophenyl-1-ureido)-(α -naphthyl-N-methylcarbamoyl) sulfide

A solution of 0.05 mol of 1-chlorothio-1-methyl-3-(3,4-dichlorophenyl) urea in 50 ml of methylene chloride was prepared by a procedure identical to that of Example 3. 1-Naphthyl-N-methyl carbamate, 8.3 g (0.04 mol) was added portionwise to the chlorothio urea at room temperature. Pyridine, 3.9 g (0.05 mol) was added and the reaction stored overnight at room temperature. The reaction was washed with water, washed with sodium bicarbonate, dried over magnesium sulfate, and evaporated under reduced pressure to give a brown oil. The oil was slurried with ether to precipitate a white solid. Recrystallization from chloroform/hexane gave the product, m.p. 123°–124.5°C. Elemental analysis showed: %S, Calc. 7.11, found 7.4; %Cl, calc. 15.8, found 15.8.

EXAMPLE 6

[3-(2-fluorophenyl)-1-methyl-1-ureido]-[3',3'-dimethyl-1'-(3,4-dichlorophenyl)-1'-ureido] sulfide

A solution of about 0.05 mol 1-chlorothio-1-methyl-3-(2-fluorophenyl) urea in methylene chloride was added dropwise to 11.65 g (0.05 mol) 3,3-dimethyl-1-(3,4-dichlorophenyl) urea and 4.74 g (0.06 mol) pyridine in 50 ml methylene dichloride. After the addition was completed, the reaction was stirred for 3 hours at about 25°C. and allowed to stand overnight. The reaction mixture was then washed with water, washed with sodium bicarbonate, washed twice with water, dried over magnesium sulfate and evaporated to give a yellow oil. The yellow oil was crystallized from hot ethanol to give the bis-urea sulfide product, m.p., 149.5°–150.5°C. Standard analysis gave:

	Calc.	Found
C %	47.3	49.7
H %	3.9	3.8
N %	13.0	13.0
S %	7.4	7.5
Cl %	16.5	16.9

EXAMPLE 7

[3-(3,4-dichlorophenyl)-1-methyl-1-ureido]-[3',3'-dimethyl-1'-(3,4-dichlorophenyl)-1'-ureido] sulfide

A solution of 1-chlorothio-1-methyl-3-(3,4-dichlorophenyl) urea was prepared from 12 g (0.055 mol) of 1-methyl-3-(3,4-dichlorophenyl) urea, 6.28 g (0.061 mol) sulfur dichloride and 5.22 g (0.066 mol) pyridine in 55 ml methylene dichloride by a procedure identical to that of Example 3. The solution of chlo-

rothio urea was added dropwise to a slurry of 11.7 g (0.05 mol) 3,3-dimethyl-1-(3,4-dichlorophenyl) urea and 3.95 g (0.05 mol) pyridine at about 25°C. and the resulting reaction mixture was stirred at about 25°C. for 2½ hours. The reaction mixture was then washed with water, washed with sodium bicarbonate solution, washed with water, dried over magnesium sulfate and evaporated under reduced pressure to give a yellow oil. The yellow oil was slurried in benzene and filtered. The filtrate was then washed through a column of silica and evaporated to give a thick oil which crystallized from ether-hexane as a white solid. Recrystallization of the white solid from isopropanol gave the bis-urea sulfide product, m.p., 145°–149°C. Elemental analysis gave: %S, calc. 6.6, found 6.7; %Cl, calc. 29.4, found 30.0.

EXAMPLE 8

Preparation of bis-(1-methyl-3-o-fluorophenyl-1-ureido) sulfide

5.6 g (0.05 mol) of freshly distilled sulfur dichloride in 10 ml of methylene chloride was added slowly to 16.8 g (0.1 mol) of 1-methyl-3-o-fluorophenyl urea and 8.5 g (0.106 mol) of pyridine in 250 ml of methylene chloride. Solution of the partially dissolved urea was effected. After being stirred 2 hours at room temperature, the mixture was washed two times with 200-ml portions of water, dried over magnesium sulfate, followed by removal of solvent under vacuum. The product was chromatographed on 200 g of silica gel eluting with ether. The crystalline product isolated by chromatography was recrystallized from benzene-hexane giving 5.5 g of crystals melting at 110°–114°C. The compound, bis-(1-methyl-3-o-fluorophenyl-1-ureido) sulfide, showed elemental analysis as follows: %S, calc. 8.75, found 8.86; %F, calc. 10.38, found 10.72. An NMR spectrum of the recrystallized material further identified the product.

EXAMPLE 9

Preparation of bis-(1-methyl-3-(3',4'-dichlorophenyl)-1-ureido) sulfide

5.6 g (0.05 mol) of sulfur dichloride in 10 ml of methylene chloride was added to a slurry of 21.9 g (0.1 mol) of 1-methyl-3-(3,4-dichlorophenyl) urea and 8.5 g (0.106 mol) of pyridine in 250 ml of methylene chloride. Solution was effected after being stirred 2 hours. The yellow solution was added to 200 ml water, causing white solid to come out of the solution. The white solid was collected on a filter and the filtrate worked up to yield more crude product. The filter cake was recrystallized from ethanol, yielding 3.7 g of white crystals of bis-(1-methyl-3-(3',4'-dichlorophenyl)-1-ureido) sulfide, melting at 188°–192°C. The elemental analysis was: %Sc, calc. 6.86, found 6.45; %Cl, calc. 30.3, found 27.87.

EXAMPLE 10

Preparation of bis-(1-methyl-3-p-fluorophenyl-1-ureido) sulfide

5.6 g (0.05 mol) of sulfur dichloride in 10 ml of methylene chloride was added slowly to a flask containing 16.8 g of 1-methyl-3-p-fluorophenyl urea (0.1 mol) and 8.5 g of pyridine in 250 ml of methylene chloride. The resulting green solution was stirred at room temperature for 2 hours, then water-washed twice, dried

and stripped. The residue was a thick, greenish oil which solidified when cooled. Recrystallization from ethanol in hexane and further washing of the crystals with hexane resulted in 7 g of bis-(1-methyl-3-p-fluorophenyl-1-ureido) sulfide having a melting point of 123°-136°C. and the following elemental analysis: %S, calc. 8.77, found 8.65; %F, calc. 10.38, found 10.3.

EXAMPLE 11

Preparation of: (a)

bis-(1-methyl-3-p-chlorophenyl-1-ureido) sulfide; and (b)

1-methyl-3-p-chlorophenyl-1-ureido-1'-p-chlorophenyl-3'-methyl-1'-ureido sulfide

5.6 g of sulfur dichloride in 10 ml of methylene chloride was added slowly to a slurry of 18.5 g of 1-methyl-3-p-chlorophenyl urea and 8.5 g of pyridine in 250 ml of methylene chloride. The resultant brown solution was stirred at room temperature overnight and was washed twice with 200 ml of water, dried over magnesium sulfate and stripped of solvent. The product was found to be a mixture of two compounds which, when separated by chromatography, was identified as: (a) bis-(1-methyl-3-p-chlorophenyl-1-ureido) sulfide having a melting point of 191°-196°C. and chemical analysis as follows: %S, calc. 8.17, found 8.18; %Cl, calc. 17.78, found 18.18; and (b) 1-methyl-3-p-chlorophenyl-1-ureido-1'-p-chlorophenyl-3'-methyl-1'-ureido sulfide having a melting point of 187°-193°C. and a chemical analysis of: %S, calc. 8.01, found 8.04; %Cl, calc. 17.17, found 17.76.

UTILITY

The sulfides of the present invention are in general herbicidal in both pre- and post-emergent applications. For pre-emergent control of undesirable vegetation, these sulfides will be applied in herbicidal quantities to the environment — e.g., soil infested with seeds and/or seedlings of such vegetation. Such application will inhibit the growth of or kill the seeds, germinating seeds

effective against weed grasses as well as broadleaved weeds. Some may be selective with respect to type of application and/or type of weed.

Pre- and post-emergent herbicidal tests on representative sulfides of this invention were made using the following methods:

Pre-emergent Test

An acetone solution of the test sulfides was prepared 10 by mixing 750 mg sulfide, 220 mg of a nonionic surfactant and 25 ml of acetone. This solution was added to approximately 125 ml of water containing 156 mg of surfactant.

Seeds of the test vegetation were planted in a pot of 15 soil and the sulfide solution was sprayed uniformly onto the soil surface at a dose of 100 micrograms per cm². The pot was watered and placed in a greenhouse. The pot was watered intermittently and was observed for seedling emergence, health of emerging seedlings, etc., 20 for a 3-week period. At the end of this period, the herbicidal effectiveness of the sulfide was rated based on the physiological observations. A 0-to-100 scale was used; 0 representing no phytotoxicity, 100 representing complete kill.

Post-emergent Test

The test sulfide was formulated in the same manner as described above for the pre-emergent test. The concentration of the sulfide in this formulation was 5000 30 ppm. This formulation was uniformly sprayed on two similar pots of 24-day-old plants (approximately 15 to 25 plants per pot) at a dose of 100 micrograms per cm². After the plants had dried, they were placed in a greenhouse and then watered intermittently at their bases as 35 needed. The plants were observed periodically for phytotoxic effects and physiological and morphological responses to the treatment. After 3 weeks, the herbicidal effectiveness of the sulfide was rated based on these observations. A 0-to-100 scale was used; 0 representing 40 no phytotoxicity, 100 representing complete kill.

The results of these tests appear in Table I.

TABLE I

Compound	Herbicidal Effectiveness Pre/Post					
	O	W	C	M	P	L

L = Lambsquarter (*Chenopodium album*)

and seedlings. For post-emergent applications, the sulfides of the present invention will be applied directly to the foliage and other plant parts. Generally they are ef-

The amount of sulfide administered will vary with the particular plant part or plant growth medium which is to be contacted, the general location of application,

i.e., sheltered areas such as greenhouses as compared to exposed areas such as fields, as well as the desired type of control. For pre-emergent control of most plants, dosages in the range of about 0.5 to 20 lbs/acre will be used. Such administration will give a concentration of about 2 to 80 ppm sulfide distributed throughout 0.1 acre-foot. For post-emergent application, such as foliar spray application, compositions containing about 0.5 to 8 lbs sulfide per 100 gal of spray will be used. Such application is equivalent to about 0.5 to 20 lbs sulfide per acre.

The herbicidal compositions of this invention comprise an herbicidal amount of one or more of the above-described sulfides intimately admixed with a biologically inert carrier. The carrier may be a liquid diluent such as water or acetone or a solid. The solid may be in the form of dust powder or granules. These compositions will also usually contain adjuvants such as a wetting or dispersing agent to facilitate their penetration into the plant growth medium or plant tissue and generally enhance their effectiveness. These compositions may also contain other pesticides, stabilizers, conditioners, fillers and the like.

What is claimed is:

1. A method for controlling undesirable vegetation which comprises applying thereto an herbicidally effective amount of a compound of the formula

wherein R¹ is hydrogen or alkyl of 1 to 6 carbon atoms; R² is alkyl of 1 to 6 carbon atoms or phenyl substituted with up to 4 fluorine, chlorine, bromine, nitro, alkyl of 1 to 5 carbon atoms, alkoxy of 1 to 4 carbon atoms, or up to 1 trifluoromethyl or trichloromethyl; R³ and R⁴ individually are hydrogen, alkyl of 1 to 6 carbon atoms, or phenyl substituted with up to 4 fluorine, chlorine, bromine, nitro, alkyl of 1 to 5 carbon atoms, alkoxy of 1 to 4 carbon atoms, or up to 1 trifluoromethyl or trichloromethyl; and R⁵ is —NR⁶R⁷ wherein R⁶ is hydrogen or alkyl of 1 to 6 carbon atoms and R⁷ is alkyl of 1 to 6 carbon atoms or phenyl substituted with up to 4 fluorine, chlorine, bromine, nitro, alkyl of 1 to 5 carbon atoms.

atoms, alkoxy of 1 to 4 carbon atoms, or up to 1 trifluoromethyl or trichloromethyl.

2. The method of claim 1 wherein R^5 is $-\text{NR}^6\text{R}^7$; R^1 and R^6 are the same, R^2 and R^7 are the same and are phenyl substituted with up to 2 fluorine, chlorine, bromine, nitro, alkyl, alkoxy or up to 1 trifluoromethyl or trichloromethyl, and R^3 and R^4 are the same and are alkyl.

3. The method of claim 2 wherein R¹ and R⁶ are hydrogen and R² and R⁷ are phenyl substituted with up to 2 fluorine, chlorine, bromine or alkyl.

4. The method of claim 3 wherein R^2 and R^7 are 2-fluorophenyl and R^3 and R^4 are methyl.

5. The method of claim 1 wherein R^5 is $-NR^6R^7$; R^1 and R^6 are hydrogen; R^2 and R^4 are the same and are phenyl substituted with up to 2 fluorine, chlorine, bromine, nitro, alkyl of 1 to 5 carbon atoms, alkoxy of 1 to 4 carbon atoms, or up to 1 trifluoromethyl or trichloromethyl; and R^3 and R^7 are the same and are alkyl.

6. The method of claim 5 wherein R^2 and R^4 are phenyl substituted with up to 2 fluorine, chlorine, bromine or alkyl.

7. The method of claim 6 wherein R^2 and R^4 are p-chlorophenyl and R^3 and R^7 are methyl.

8. The method of claim 1 wherein R^5 is $-NR^6R^7$; R^4 is phenyl substituted with up to 2 fluorine, chlorine, bromine, nitro, alkyl of 1 to 5 carbon atoms, alkoxy of 1 to 4 carbon atoms, or up to 1 trifluoromethyl or trichloromethyl; R^6 is alkyl and R^7 is alkyl.

9. The method of claim 8 wherein R^1 is hydrogen, R^2 is 2-fluorophenyl, R^3 is methyl, R^4 is 3,4-dichlorophenyl, R^6 is methyl and R^7 is methyl.

10. The method of claim 1 wherein R^3 and R^4 individually are alkyl.

11. An herbicidal composition comprising an herbicidally effective amount of a compound defined in claim 1 and a biologically inert carrier.

12. The composition of claim 11 wherein R^5 is $-NR^6R^7$, R^1 and R^6 are the same, R^2 and R^7 are the same and are phenyl substituted with up to 2 fluorine, chlorine, bromine, nitro, alkyl, alkoxy or up to 1 trifluoromethyl or trichloromethyl, and R^3 and R^4 are the same and are alkyl.

13. The composition of claim 12 wherein R¹ and R⁶ are hydrogen and R² and R⁷ are phenyl substituted with up to 2 fluorine, chlorine, bromine or alkyl.

14. The composition of claim 13 wherein R² and R³ are 2-fluorophenyl and R³ and R⁴ are methyl.

UNITED STATES PATENT AND TRADEMARK OFFICE
CERTIFICATE OF CORRECTION

PATENT NO. : 3,925,056
DATED : December 9, 1975

INVENTOR(S) : Melancthon S. Brown, Gustave K. Kohn

It is certified that error appears in the above-identified patent and that said Letters Patent are hereby corrected as shown below:

Title page, [75], Inventors should read --Melancthon S. Brown, deceased, late of Berkely, California; by Gustave K. Kohn, administrator, and Gustave K. Kohn, Berkely, California.--

Signed and Sealed this
